BRUSH AND PROCESS FOR FORMING
THE SAMEAlfred L. Le Febvre, Windsor, Conn., assignor to
The Fuller Brush Company, Hartford, Conn., a
corporation of Connecticut

Application December 16, 1941, Serial No. 423,199

5 Claims. (Cl. 300—21)

This invention relates to that type of brushes comprising two ends, usually forming the core of the brush, which are secured within a handle, more especially the brush material being secured to the core by twisting two pieces of wire together and the ends which are secured in the handle being extended beyond the brush structure, and an object of the invention, among others, is the production of a brush of this type in which an extreme degree of rigidity is obtained between the brush and the handle, which is particularly effective in a brush of the type shown herein wherein such brush is bent into looped form.

One form of a brush embodying the invention and in the construction and use of which the objects herein set out, as well as others, may be attained is illustrated in the accompanying drawing, in which—

Figure 1 is a side view of a brush embodying the invention with the handle broken away to show construction.

Figure 2 is an end view of the handle, scale enlarged.

Figure 3 is a view in cross section through the shank of the brush.

Figure 4 is a view in section on a plane denoted by the broken line 4—4 of Fig. 1.

Figure 5 is a view illustrating the step of heating the shank of the brush.

Figure 6 is a view illustrating the step of inserting the heated shank into the handle.

Figure 7 is a view illustrating the step of hardening the softened portion of the handle after insertion of the brush shank therein.

It has been a difficult matter in the manufacture of brushes of this type to so unite the handle and the brush that the latter will be rigidly secured in place. In previous operations when the tangs or ends of the brush were inserted in holes in the end of the brush handle no matter how tightly they might be secured there was a weaving action permitted by the resiliency of the wire, and the loop form of brush provided a leverage that increased this tendency to weaving action with a result that the brush structure instead of being rigid was more or less flexible and resilient which is an undesirable feature. To overcome this objectionable result the holes were filled with an adhesive which hardened and became solid, but this did not overcome the difficulty as the adhesive did not secure the rigidity needed.

It was then proposed to drill two holes into the end of the handle in such close proximity that the holes would cut into each other so that the two tangs or ends of the brush would touch each other

when inserted in the holes. The two tangs were then welded together along their meeting surfaces and they were then inserted into the holes which were made sufficiently small to secure a tight fit. This did not secure the necessary rigidity even when the adhesive hereinbefore referred to was employed.

In developing the invention disclosed herein the handles are formed of a composition of matter, 10 different compositions being suitable for the purpose. A handle formed from a composition which softens under heat is employed, two holes are bored into the end of the handle cutting one into the other, and the two tangs or shanks are 15 welded together as hereinbefore explained. The holes are made small enough to provide a comparatively tight fit for the tangs or shanks and these are welded together to provide a stem. This stem is then heated to a suitable degree, an electric heater satisfying this procedure and the tangs thus heated are inserted into the tight holes the walls of which under the influence of the heat become softened and slippery so that the shank or 20 stem is forced into place in the holes provided for it. During the insertion of the shank into the holes a blast of air is directed against the point where the insertion is being made, this for the purpose of removing the smoke from contact with the bristles or brush fibers, which when of light 25 color, would otherwise be discolored. This smoke is blown into a hood which is under suction and which acts to carry the smoke and fumes away from the operator.

Promptly after the insertion of the tang within 30 the handle the latter is submerged in water to effect a hardening and setting of the composition of which the handle is composed and it has been found that the most desirable effects are produced when the handles are thus submerged 35 in a current of running water.

The improved brush and the process for uniting the handle and the brush as illustrated in the drawing herein embody a brush and a handle generally denoted by the numerals 5 and 6, respectively. The handle, as hereinbefore explained, is formed from a composition of matter which will soften under the influence of heat and the brush is formed of bristles or other brush material 7 in a manner common to the manufacture 40 of brushes of this type. Two holes 8 are formed in the handle, these holes being so closely positioned that they cut one into the other forming an opening 9.

The two ends 10 of the brush are placed in contact and welded as at 11. The shank thus formed

is heated as by an electrical heater 12, the ends being placed between the electrodes of the heater. The tang or stem is then inserted manually into the holes 8 and forced into such holes. The contact of the heated tang with the walls of the holes softens the material and causes it to become slippery so that the tang is quite readily inserted. During this insertion the point of operation is placed between a nozzle 13 from which a blast of air is directed upon the handle and tang and the smoke is blown toward the mouth of a hood 14 in which a suction is produced to take away the smoke and fumes.

After this operation the handle with the brush secured thereto is placed in a receptacle in which a current of running water is maintained as by supply from a tap 15, the surplus water being disposed of by a drain 16.

I claim:

1. A brush comprising a handle member having two holes in one end cutting into each other to remove the dividing wall between them, and a brush member comprising a wire with brush material secured thereto and bent into loop form with bared ends extending into said holes and welded together contiguous one to the other therein for mutual support thereof and held therein by fused material of the walls of the holes filled into the crevices and depressions of said bared ends and thereby constituting an integral mass comprising the handle and filling.

2. A brush comprising a handle member having two holes in one end cutting into each other to remove the dividing wall between them, and a brush member comprising a core formed of twisted strands of material with brush material secured in said twisted core, said brush member being bent into loop form with bared ends extending into said holes and welded together contiguous one to the other therein for mutual support thereof and held therein by fused material of the walls of the holes filled into the crevices and depressions of said bared ends and thereby

constituting an integral mass comprising the handle and filling.

3. A brush comprising a handle member having two holes in one end cutting into each other to remove the dividing wall between them thereby creating oppositely disposed ribs extending lengthwise of the holes, and a brush member comprising a wire with brush material secured thereto and bent into loop form with bared ends welded together thereby forming grooves to receive said ribs, said bared ends being extended into said holes and held therein by fused material of the walls of the holes filled into the crevices and depressions of said bared ends and thereby constituting an integral mass comprising the handle and filling.

4. The process for making a brush that consists in providing a handle member of material fusible by heat, forming two holes in the end of the handle member cutting into each other to remove the dividing wall between them, providing a brush having a shank with depressions and crevices in its outer surfaces, heating said shank, and then inserting it into said holes with the shank members contiguous one to the other therein for mutual support thereof, said heating fusing the walls thereof to effect entry of the fused material into said depressions and crevices.

5. The process for making a brush that consists in providing a handle member of material fusible by heat, forming two holes in the end of the handle member cutting into each other to remove the dividing wall between them, providing a brush having a core of twisted wire to secure brush material therein and having a shank comprising the bared ends of the brush member, welding said bared ends together to form grooves extending lengthwise of the shank on opposite sides thereof, heating said shank, and then inserting it into said holes thereby fusing the walls thereof to effect entry of the fused material into said grooves.

ALFRED L. LE FEBVRE.
